RING GUARD

Fannie Berman, Paterson, N. J.

Application September 28, 1935, Serial No. 42,650

8 Claims. (Cl. 63—17)

This invention relates generally to protectors for jewelry and more particularly to protectors for rings and the like.

The main object of this invention is the provision of structure which will protect the principal surface of a ring from damage or abrasion, thus obviating the necessity for the removal of the ring from the finger of the wearer while the wearer is engaged in using the hands in work. Since with the utilization of this ring-guard it is not necessary to remove the ring, the liability of loss is greatly reduced, it being a well known fact that many valuable rings are lost in this manner, especially when the ring is removed while the wearer is performing various kinds of washing.

Another principal object of this invention is the provision of structure which acts to prevent the dislodgment of valuable gems mounted in rings, a condition which is likely to occur when the gem is struck accidentally against some mechanical obstruction. This protector not only prevents the gem from undesirably coming into contact with other objects, but also serves as a container within which the gem will be retained if the gem should become accidentally detached from the mounting means integral with the ring through some mechanical failure of said means.

Another object of this invention is the provision of a ring-guard which, while performing the above mentioned services, presents a pleasing and esthetic appearance, is light in weight and in a sense adds to the general appearance of the ring.

Another advantage of this invention is the fact that this ring-guard is easily attached to and detached from the ring, thereby making its use simple and expedient.

A still further advantage of this invention lies in the simplicity of structure thereof and the consequent economies in its manufacture.

These objects and further ends and advantages will more fully appear in the progress of this disclosure and as pointed out in the appended claims.

In the drawing:

Figure 1 is a plan view of one species of the ring-guard, the subject of this invention.

Figure 2 is a bottom view of the structure shown in Figure 1.

Figure 3 is a view in perspective showing the structure of Figure 1 as applied to a ring having a mounted gem thereon, the crown or cover portion of the guard being broken away to show the position of the gem therebeneath.

Figure 4 is an enlarged longitudinal vertical sectional view of the structure shown in Figure 1.

Figure 5 is a transverse sectional view of Figure 4 along the plane 5—5 thereon.

Figure 6 is a transverse sectional view taken similarly to Figure 5 but showing an alternative structure for attaching the ring-guard to the ring.

Figure 7 is an enlarged side elevational view of Figure 1 taken from the plane 7—7 thereon.

Numerals 10 indicates a finger ring and 11 a gem mounted thereon in any well known manner.

The crown or cover portion 12 comprises a relatively horizontal plate 13 and integral depending vertical longitudinal side-walls 14 and 15 transverse side-walls 16. As is obvious to those skilled in the art to which this device pertains, the cover 12 may be formed in any suitable configuration. The size and shape of said cover is determined on the inside thereof by the configuration of the gem 11 and the supporting structure therefor or, in the case of a ring not having a mounted gem thereon, by the configuration of the main surface of said ring. On the other hand, the configuration of the outside of said cover is determined solely by the appearance desired and to some extent by mechanical considerations.

Affixed in any suitable manner, as for example by soldering or brazing, are two downwardly extending brackets 16. Brackets 16 are shaped to embrace adjacent the lower extremities thereof, the ring 10 but their general configuration is determined in a manner similar to that set forth above in connection with the cover 12. While the brackets 16 are shown in the drawing as being affixed to the cover 12, it is considered as being within the scope of this invention if said brackets are formed integrally from the same substance of which the cover 12 is composed and may be formed simultaneously therewith. Brackets 16 adjacent their extremities are provided with small latches 17 which are pivotally connected at one end thereof to a lateral edge of said brackets, as for example at 21. The said pivotal connection is constructed in any suitable manner known in the art, as for example forming a loop in the pivotal end of the latch 17 about a wire which serves as a pintle therefor and said wire is soldered to the portion 17 or, as shown, the portion 17 is pierced with a longitudinal narrow slot and the pivotal end of the latch 17 is inserted therethrough and bent upon itself to form the loop portion thereof 18.

Latches 17 are adapted for movement as indi-

cated by the dot dash lines in Figure 5 and the free ends thereof are provided with integral inwardly offset portions 19 which are adapted for resilient contact with the portions 20 of brackets 5 16 opposite the portion 17 aforesaid and therefore capable of convenient detachable attachment thereof.

In use the ring 10 is removed from the finger and with the latches 17 in the open position 10 thereof, the ring-guard is placed over the ring so that the lower extremities of the brackets 16 embrace said ring. The latches 17 are then snapped into their closed position and the ring is replaced upon the finger. It may be seen that 15 the detachable attaching mechanism associated with the latches 17 may be comparatively light in structure because the lower surface of the latches 17 is in contact with the finger upon which the ring is placed. Therefore, it may be seen that any slight disengagement of the portion 20 with the portion 19 will not materially affect the security of the ring-guard on the ring.

The alternative structure shown in Figure 6 makes provision for attaching the ring-guard to 25 the ring by merely snapping it into place without the necessity of removing the ring from the finger in order to do this. This structure is somewhat less secure than the foregoing one, but offers the advantage of greater facility in use. 30 As seen at Figure 6, the bracket 16' is composed of a suitably resilient material and the lower longitudinal edges 17' thereof are bent inwardly toward each other. It may thus be seen that the lower extremities of the brackets 16' perform in the manner of clips and the lower edges 35 17', in springing inwardly, cause the bracket at this point to securely embrace the ring 10.

While the cover 12 is shown in the drawing as being continuous in surface, it is to be considered within the scope of this invention to provide the same with suitable perforations or 40 cut out portions so that although the gem may be seen therefrom, the configuration of these openings is small enough to restrict the passage there-through of the gem should the gem become detached therewithin and, since the plate 13 is held in the operative position thereof at a point somewhat above the level of the gem 11, physical 45 obstructions or surfaces liable to abrade the gem 50 will be prevented from coming in contact with said gem.

I wish it distinctly understood that minor changes and variation in the structure, material and integration of the parts may be indulged 55 in without departing from the spirit of the invention and the scope of the appended claims.

I claim:

1. As a new article of manufacture, a ring-guard comprising a cover adapted to protect the 60 main surface of a ring, a pair of brackets affixed to said cover and adapted to engage portions of said ring adjacent the main surface.

2. As a new article of manufacture, a ring-guard comprising a cover adapted to protect the main surface of a ring, a pair of brackets affixed to said cover and adapted to engage portions of said ring adjacent the main surface and means 5 on said brackets to detachably attach them to the said portions.

3. As a new article of manufacture, a ring-guard comprising a cover adapted to protect the main surface of a ring, a pair of brackets affixed 10 to said cover and adapted to engage portions of said ring adjacent the main surface and having the longitudinal edges thereof inwardly bent and thereby adapted to detachably engage the said ring by clipping thereabout. 15

4. As a new article of manufacture, a ring-guard comprising a cover adapted to protect the main surface of a ring, a pair of brackets affixed 20 to said cover and adapted to engage portions of said ring adjacent the main surface, a pivotal latch on each of said brackets adapted to enclose the portion of the ring thereat within each bracket and having the free end of said pivotal latch adapted for detachable engagement 25 with the edge of each bracket thereat.

5. As a new article of manufacture, a ring-guard for rings having gems thereon comprising a crown portion adapted to cover said gem, a pair of brackets affixed to said crown portion and adapted to engage portions of said ring adjacent 30 the gem carrying portion of said ring.

6. As a new article of manufacture, a ring-guard for rings having gems thereon comprising a crown portion adapted to cover said gem, a pair of brackets affixed to said crown portion and 35 adapted to engage portions of said ring adjacent the gem carrying portion of said ring and means on said brackets to detachably attach them to the said ring.

7. As a new article of manufacture, a ring- 40 guard for rings having gems thereon comprising a crown portion adapted to cover said gem, a pair of brackets affixed to said crown portion and adapted to engage portions of said ring adjacent the gem carrying portion of said ring and 45 having the longitudinal edges thereof inwardly bent and thereby adapted to detachably engage the said ring by clipping thereabout.

8. As a new article of manufacture, a ring-guard for rings having gems thereon comprising 50 a crown portion adapted to cover said gem, a pair of brackets affixed to said crown portion and adapted to engage portions of said ring adjacent the gem carrying portion of said ring, a pivotal latch on each of said brackets adapted 55 to enclose the portion of the ring thereat within each bracket and having the free end of said pivotal latch adapted for detachable engagement with the other edge of each bracket thereat. 60

FANNIE BERMAN.
